INVENTOR.

UNITED STATES PATENT OFFICE.

RICHARD D. KNIGHT, OF PROVIDENCE, RHODE ISLAND.

FLEXIBLE KEY-RING.

SPECIFICATION forming part of Letters Patent No. 674,775, dated May 21, 1901.

Application filed February 15, 1901. Serial No. 47,493. (No model.)

To all whom it may concern:

Be it known that I, RICHARD D. KNIGHT, a citizen of the United States, residing at Providence, in the county of Providence and State 5 of Rhode Island, have invented certain new and useful Improvements in Flexible Key-Rings, of which the following is a specification, reference being had therein to the accompanying drawings.

Like letters indicate like parts.

Figure 1 is a side elevation of the ends of the chain portion of my improved flexible key-ring and the locking means therefor in engagement. Fig. 2 is a side elevation of 15 one end of said chain and the holding-disk thereof, together with a diametrical section of the interiorly-threaded locking tube or barrel connected therewith. Fig. 3 is a side elevation of the opposite end of said chain 20 and the locking-disk therefor, together with a diametrical section of the exteriorly-threaded locking tube or barrel connected therewith. Fig. 4 is a side elevation of said ends of the chain and their holding-disks, together 25 with a section of said two locking tubes or barrels in engagement. Fig. 5 is a side elevation of one end of said chain and of the first-named locking tube or barrel. Fig. 6 is a side elevation of the opposite end of said 30 chain and of the second-named locking tube or barrel.

My invention relates to a flexible chain key-ring and locking devices therefor; and it consists of the novel construction and combination of the several elements, as herein-after particularly described, and specifically set forth in the claim.

In the drawings, A represents one end of a chain, and B the opposite end. At the tip 40 or extremity of the end A of the chain is soldered or otherwise fastened a circular disk C, and on the tip or extremity of the opposite end B of the chain is similarly secured a circular disk D.

E is a tubular barrel having an interior screw-thread, as shown in Figs. 2 and 4, and also an annular flange a, leaving a central aperture b, through which the chain freely passes.

F is a tubular barrel having an annular flange c, which leaves a central aperture d, through which the chain freely passes. A

tube G has one portion of its outer surface smooth, which fits in the bore of the barrel F and is secured there in position in any suitable manner, and the other portion of said tube G is made with an exterior screw-thread, as seen in Figs. 3 and 4. The tube G is of a less diameter than the barrel F, and therefore when inserted in position there is an annular shoulder e, formed, as shown in Figs. 3, 4, and 6. The unthreaded or cylindrical portion of the tube G is shorter than the barrel F and when inserted in the barrel leaves an annular recess f between the end of said tube G and the inner surface of the flange c of the barrel F. As a consequence of this construction, when the disk D of the chain end B has been placed in the barrel F the inner end of the tube G prevents the chain 70 from longitudinal movement within the barrel F, although it does not interfere with the rotary movement of the barrel F upon the chain B or of the chain B within the barrel F. In like manner when the tube G is screwed 75 into the barrel E, as the threaded portion of the tube G is shorter than the barrel E, there is formed an annular space between the end of the tube G and the inner surface of the flange a, and the chain end A is prevented 80 from longitudinal movement in either direction, although a rotary movement of the barrel E upon the chain end A is allowed. The tube G should be screwed into the barrel E until the end of the barrel E comes into snug 85 contact with the shoulder e of the tube G, as shown in Figs. 1 and 4.

A flexible chain, preferably having close links and provided with locking devices, as shown, constitutes a very desirable means of 90 safely carrying keys in the pocket and is much superior to the rigid or split spring-ring commonly used. The keys are easily placed upon this flexible ring, because each locking-barrel is so small in diameter as to readily pass 95 through the bow of the key.

By means of the holding-disks C D the detaching of the ends A B of the chain from the locking-barrels E F is prevented.

It is seen that the locking-barrels are rotatable upon the chain both when separate and when screwed together, and by this arrangement the barrels E F are screwed together without kinking the chain, which would be

impossible if either or both of said barrels were soldered upon the chain or otherwise immovably fastened thereto. It is necessary that both the barrels E F should swivel freely 5 on the chain, for if one of said barrels is fast upon the chain and the other is loose thereon then although the loosely-turning barrel may be engaged with the other barrel without kinking the chain, yet by the various movements to 10 which the flexible ring and the bunch of keys thereon are liable when carried in the trouser-s-pocket kinks are formed which turn and unscrew the fastened barrel and soon separate it from the other barrel.

15 I claim as a novel and useful invention and desire to secure by Letters Patent—

The improved flexible key-ring herein described, consisting of the chain A B having at one end the circular disk C fastened thereon 20 and at the opposite end the circular disk D fastened thereon, the cylindrical locking-

barrel E having an interior screw-thread, the inwardly-directed annular flange *a* and the central aperture *b* through which said chain passes, the cylindrical locking-barrel F having the inwardly-directed annular flange *c* and the central aperture *d* through which said chain passes, and also having the tubular extension G fitting in the bore of the barrel F so as to leave an interior annular recess *f* and an exterior shoulder *e*, the protruding portion of which tubular extension is exteriorly screw-threaded and engageable with said interiorly-screw-threaded cylindrical locking-barrel E, substantially as shown. 25 30 35

In testimony whereof I affix my signature in presence of two witnesses.

RICHARD D. KNIGHT.
